(57) **CLAIM**

The ornamental design for a kidney stone collection device, as shown and described.

DESCRIPTION

FIG. 1 is a perspective view of the kidney stone collection device showing my new design;

FIG. 2 is a top view thereof;

FIG. 3 is a front view thereof; the front view being identical to the left side view, the right side view, and the back view;

FIG. 4 is a bottom view thereof; and,

FIG. 5 is a cross-sectional view taken at line 5—5 in FIG. 2.
